CAP AND STOPPER COMBINATION FOR HOSE OR THE LIKE

Alexander Chakine, New York, N.Y.

Application March 26, 1958, Serial No. 50,194

Term of patent 14 years

(Cl. D91—1)

Fig. 1 is a side elevational view of a cap and stopper combination for hose or the like embodying my new design and illustrating the combination open and in position for use as a cap;

Fig. 2 is a view similar to Fig. 1 but illustrating the combination closed;

Fig. 3 is a side view partially in section illustrating the combination closed and in position for use as a stopper; and

Fig. 4 is a top plan view of the cap and stopper combination as seen in Fig. 2.

I claim:

The ornamental design for a cap and stopper combination for hose or the like, substantially as shown.
